United States Patent

Des. 240,975
Patented Aug. 17, 1976

240,975

GLOVE WITH RAISED BACKING

John R. Gregory, 241 W. 35th St.,
National City, Calif. 92050

Filed May 8, 1975, Ser. No. 575,449

Term of patent 14 years

Int. Cl. D2—06

U.S. Cl. D2—361

FIG. 1 is a perspective view, from the back, of a glove with raised backing, showing my new design; and

FIG. 2 is a perspective view from the front thereof.

I claim:

The ornamental design for a glove with raised backing, as shown.
